(57) **CLAIM**

The ornamental design for a mounting plate for a table top, as shown and described.

DESCRIPTION

FIG. 1 is a top perspective view of the mounting plate for a table top;

FIG. 2 is a bottom perspective view of the mounting plate for a table top;

FIG. 3 is a top plan view of the mounting plate for a table top;

FIG. 4 is a right side elevation view of the mounting plate for a table top;

FIG. 5 is a left side elevation view of the mounting plate for a table top;

FIG. 6 is a front elevation view of the mounting plate for a table top;

FIG. 7 is a bottom plan view of the mounting plate for a table top;

FIG. 8 is another bottom perspective view of the mounting plate for a table top with a female mounting plate; and,

FIG. 9 is another bottom perspective view of the mounting plate for a table top with a female mounting plate attached. The broken lines in the drawings illustrate portions of the mounting plate for a table top which form no part of the claimed design.

1 Claim, 5 Drawing Sheets
